JOSEPH A. SANDFORD, JR., OF EAST LIVERPOOL, OHIO, ASSIGNOR TO THE R. THOMAS AND SONS COMPANY, OF EAST LIVERPOOL, OHIO, A CORPORATION OF OHIO.

ELECTRIC-CABLE ATTACHMENT.

1,215,201.

Specification of Letters Patent.

Patented Feb. 6, 1917.

Application filed February 14, 1913. Serial No. 748,440.

To all whom it may concern:

Be it known that I, JOSEPH A. SANDFORD, Jr., a citizen of the United States of America, and residing in the city of East Liverpool, in the county of Columbiana and State of Ohio, have invented a certain new and useful Improvement in Electric-Cable Attachments, of which the following is a specification.

10 My invention relates to electric cable attachments and particularly to attachments for use with strain insulator supports of high-tension electric cable lines. The object of my invention is to provide an attachment of improved type which at the same time is readily manufactured and installed.

In the accompanying drawings,

Figure 1 is a broken side elevation of an attachment embodying my invention in one form;

Fig. 2 is an inverted plan view of the same;

Fig. 3 is a cross section through the attachment on the line 3—3, Fig. 1;

25 Fig. 4 is a side elevation of this attachment as installed in a high tension line;

Figs. 5 and 6 are plan and side elevations respectively of a modified eye for one end of the attachment; and

30 Fig. 7 is a side elevation showing an attachment with a modified guide arm.

The present attachment comprises in the form shown an elongated body portion 10 provided at one end with a longitudinal channel or groove 11 to accommodate the wire cable 12, the bottom of the groove being preferably serrated as at 13, to secure a firm grip upon the wire. The other end, which is substantially alined with the wire-receiving end, is provided with an eye 14 which the hook 15 of the terminal strain insulator 16 engages. Strengthening ribs 17, preferably in channel form, extend from the eye 14 toward the middle of the body, but terminate at a point such that they may not interfere with the cable 12 as it passes to the jumper loop 18. A clamping plate 19 is preferably provided which overlies the grooved end of the clamp and is shaped to coöperate with the latter, being moved into clamping position by the nuts 20 on bolts 21 which pass through lugs 22, 23 perforated in register on both sides of the wire-receiving grooves.

55 Intermediate the ends of the attachment

body an arm 24 is formed to guide the cable from the clamp to its jumper loop 18. This arm has its base at the end of the clamp proper and flares downward on a gradual curve so that the cable may not be injured by a sharp bend at this point. Retaining webs 25, 26 are formed on this guide arm to properly position and retain the cable. The upper web 25 joins the lower edge of the arm and forms an open trough in which the cable lies. The web 26, at the lower end of the arm, joins the other edge of the arm and thus forms an oppositely faced open trough which serves to keep the cable down in proper position. The rounded lip 27 finishes the end of the web 26 so that no sharp edge which might injure the cable is presented. The webs are spaced apart to afford an opening 27 which permits the cable to be slightly bent down at this point during adjustment beneath the web 26.

The construction described presents the advantage over clamps of this type in which a jumper guide arm is provided, in that the clamp plate 19 engages that portion of the cable passing through the clamp which lies in alinement with the long cable span and the axis of the strain insulators. Thus the portion of the cable which is deflected through the guide arm 24 to form a jumper loop to the next span, is entirely relieved from the strain of the span and is under substantially no injurious stress at the bends in the cable as is the case when the clamp is located on the deflecting arm. Furthermore, the present construction makes it possible, as illustrated in Fig. 7, to make the guide arm 28 of such length that should the cable be brought up taut beneath the lower lip 27 of the guide arm, the portion of the cable which has formed the jumper loop, will be held out of contact with the edges of the insulators and danger of short-circuiting when the insulators are wet, eliminated.

It is unimportant just what form the eye end of the clamp takes. Thus as shown in Figs. 5 and 6, a single eye 29 instead of a pair of perforated wings, may be employed. Various other modifications of detail will readily suggest themselves.

I claim as my invention:

1. A device of the character described having in alinement a clamping portion and an eye portion, and between them a deflecting guide arm at an angle to the body of the

clamp to deflect and guide the cable gripped by the clamp, together with oppositely faced guide webs on said deflecting arm engaging the cable on its upper and lower surfaces.

5 2. A device of the character described having in alignment a clamping portion and an eye portion, and between them a deflecting guide arm at an angle to the body of the clamp to deflect and guide the cable gripped by the clamp, together with oppositely faced 10 guide webs spaced longitudinally apart on said deflecting arm.

3. A cable jumper clamp of the character described, having in alignment a cable 15 clamping portion and a portion having

means for attaching the device to a suspension insulator, in combination with a deflecting arm rigid with said device and having means to freely engage the jumper loop of the cable, said means comprising oppositely 20 faced guide webs extending from the upper and lower margins of said arm and spaced longitudinally apart thereon.

In testimony whereof I have signed my name to this specification, in the presence of 25 two subscribing witnesses.

JOSEPH A. SANDFORD, JR.
